SHELF

Merton H. Heacox, Lodi, Calif.

Application May 3, 1949, Serial No. 2,407

Term of patent 3½ years

(Cl. D33—3)

To all whom it may concern:

Be it known that I, Merton H. Heacox, a citizen of the United States, residing at Lodi, in the county of San Joaquin and State of California, have invented a new, original, and ornamental Design for Shelf, of which the following is a specification, reference being had to the accompanying drawing, forming a part thereof.

The figure of the drawing is a perspective view of the shelf, showing my new design.

I claim:

The ornamental design for a shelf, as shown.

MERTON H. HEACOX.
